UNITED STATES PATENT OFFICE

2,291,971

MATERIAL HANDLING APPARATUS

Jacob H. Lienau, New York, and Jacob J. Neuman, South Salem, N. Y.

Application June 15, 1940, Serial No. 340,814

10 Claims. (Cl. 212—132)

This invention relates to material handling apparatus, and more particularly to a means for handling material which is unloaded from a vessel or other carrier and conveyed to a storage means.

This invention is an improvement over the conveyor system and monorail hoist disclosed in my Patent No. 1,988,855 and divisions thereof.

An object of this invention is to provide a system of traveling hoists and conveyors associated therewith for handling materials in bags or other containers.

A further object of this invention is to provide an improved traveling conveyor in the form of a stabilized sling.

A still further object of this invention is to provide a means for damping the swinging or oscillatory movement of the hoist or conveyor at the point where the material is weighed, so as to permit accurate weighing of the material.

A further object of this invention is to provide a means for automatically reducing the speed of travel of the loaded hoists when the hoist approaches the weighing station.

With the foregoing and other objects in view, the invention will be more fully described hereinafter, and will be more particularly pointed out in the claims appended hereto.

In the drawings, wherein like symbols refer to like or corresponding parts throughout the several views:

Figure 1 is a perspective view of the general conveyor arrangement or system embodying this invention.

Figure 2 is a detail side elevation of a hoist used with this invention.

Figure 3 is a detail end elevation of the hoist.

Figure 4 is a fragmentary top plan of the hoist.

Figure 5 is an enlarged fragmentary end elevation of the hoist.

Figure 6 is a fragmentary side elevation of a rail and a portion of the hoist carriage.

Figure 7 is a detail side elevation, partly in section, of the carriage stopping means.

Figure 8 is a top plan of the carriage stopping means.

Figure 9 is a perspective view of the shoe and slide embodied in the carriage stopping means.

Figure 10 is a fragmentary end elevation of the hoist controlling sleeve.

Figure 11 is a detail front elevation of the structure shown in Fig. 10.

Figure 12 is a fragmentary vertical section of the braking means for the hoist.

Figure 13 is an enlarged vertical section of the braking means shown in Fig. 12.

Figure 14 is a diagrammatic view of the electric circuits embodied in this invention.

5 Referring to the drawings and first to Figure 1, the numeral 25 designates generally a wharf or pier which has moored along side thereof a vessel designated V. The dock or wharf 25 has mounted thereon adjacent the vessel V, a pair of looped rails or tracks 26 and 27. These rails or tracks 26 and 27 are supported by means of a supporting structure generally designated as 28. This supporting structure comprises a pair of longitudinally extending frame members 29 and 30 which are connected together in parallel relation by means of a plurality of transversely extending supporting beams 31. The horizontal frame structure comprising the beams 29, 30 and 31, is supported above the surface of the pier or dock 25 by a plurality of vertical posts or supporting members 32.

20 The tracks or rails 26 and 27 are formed from I beams, and include parallel longitudinal rail members 33 and 34, and an outer end and substantially semicircular connecting member 35 connecting the outer ends of rails 33 and 34 together. The track 27 comprises side or longitudinal rails 36 and 37 which are secured to the frame structure 28 on the under side of the transverse beams 31, and the outer ends of the rails 36 and 37 are connected together by means of an arcuate and substantially semicircular connecting rail 38. The rail 33 is in alignment with the rail 36 and the rail 34 is in alignment with the rail 37.

25 At the inner or confronting ends of the rails 33, 36, 34, and 37 respectively, there are positioned a pair of stub rails 39 and 40 which are supported from angled beams 41 and 42 respectively. An arcuate rail 43 is secured to the under sides of the beams 41 and 42, outwardly from the adjacent ends of the rails 33 and 40, and is adapted to be connected by means of switch structures, as will be hereinafter described to the inner or adjacent ends of the rails 33 and 34. A second arcuate rail 44 is secured to opposite beams 41 and 42, and is adapted by means of switch structures, to be hereinafter described, to be connected to the adjacent or inner ends of the rails 36 and 37. The rails 39 and 40 are adapted to be used when the hereinafter described switch is moved to a position to cut out the arcuate rails 43 and 44, and thus form a long endless track including the rails 33, 34, 36, and 37.

A plurality of combined hoists and carriers 110 are mounted on the rails 26 and 27 and are adapted to carry a load of bags B in slings. The slings carried by the carrier are moved past a weighing station W where the load is weighed, and it will be understood that each rail section 26 and 27 is provided with a similar weighing station at a suitable point on the shore side of the rails. After the carriers 110 pass the weighing station W, they move along the rail 34 to an unloading station U, at which point there are positioned a pair of endless conveyors 111 and 112. These conveyors 111 and 112 are positioned at right angles to the rail 34 and discharge the bags onto conveyors 113 and 114 respectively. The conveyors 113 and 114 are of the bag discharging type more fully described in my Patent No. 1,911,525.

Referring now to Figures 4 to 8 inclusive, there is disclosed the detailed construction of the hoist and load stabilizing structures including the carriage which engages the monorail. The carriage or carrier includes a frame structure 127 which is provided at its front end with a forwardly projecting extension 128 terminating in an enlarged head 129 carrying a bumper 130. The rear end of the frame 127 includes an extension 131 terminating in an enlarged head 132 in which a bumper 133 engages. The frame 127 is provided at the front portion thereof with a pair of upstanding plates 134 and 135 between which two pairs of flanged wheels 136 and 137 are journaled. The rear extension 135 has secured thereto a truck frame structure including upstanding plates 138 and 139 between which two pairs of flanged wheels 140 and 141 are journaled. These wheels are adapted to engage the lower flange 142 of the mono-rail on opposite sides of the web 143. The front truck structure including the plates 134 and 135 and the two pairs of wheels 136 and 137 form the driving means for the carrier.

A motor 144 is supported below the forward truck and is operatively connected to the forward pair of wheels 136 by a reduction gear structure mounted in the housing 134.

A bowed spring or resilient bumper 146 extends rearwardly of the rear truck comprising the truck plate members 138 and 139, and this bowed spring 146 is provided with returned end portions 147 and 148 which are secured by fastening members 149 and 150 respectively to the plates 138 and 139 respectively. A spring 151 is secured by fastening means 152 to the spring 146 forwardly of the plate 138 and is secured by fastening member 153 to the forward portion of the plate 138. A second spring 154 is secured by a fastening member 155 to the spring 146 opposite from the fastening member 152 and the forward or upper end of the spring 154 is secured by fastening member 156 to the rear end of the plate 139. In this manner the spring 146 is resiliently supported at the rear end of the frame structure 127.

A pair of depending bars or arms 157 are secured to the under side of the frame 127 and a motor platform 158 provided with upwardly projecting side members 159 is secured to the depending members 157 by fastening members 160. The platform 158 is provided with a pair of downwardly extending plates 161 between which a tubular equalizing member 162 is slidably mounted. This equalizing member 162 is substantially square in transverse section, and includes side

plates 163 and 164, and end plates 165. The side plates 163 and 164 are of substantially flat configuration being provided with an upwardly reducing upper end portion 166 through which a shaft 167 engages. The shaft 167 is loosely mounted in a vertically disposed slot 168 carried by a plate 169 secured to the depending member 161 adjacent the lower portion thereof and the equalizing member 162 is adapted to gravitationally move downwardly to normally hold the shaft 167 in the lower end of the slot 168.

The platform 158 is provided with a hoisting motor 170 connected to a reduction gear 171, and a winding drum 172 is connected to the gear 171, and is positioned between the plates 159. A flexible hoisting cable 173 is wound about the drum 172 and connected at one end, as at 174, to a depending member carried by the platform 158.

A sheave 175 engages the cable 173 and is provided with a hook 176 to which the sling may be secured. When the sling is engaged with the hook 176, the motor 170 is operated to wind the cable 173 on the drum 172 and draw the sheave upwardly into the tubular equalizing member 162. When the upper end of the load carried by the hook 176 engages the lower end of the equalizer 162 the tubular member 162 will be moved upwardly for the distance permitted by the length of the slot 168. The swinging movement of the equalizer 162 is retarded by means of an air cylinder 175^a secured as by fastening member 176^a to an angle bar or support 177 which is fixed to the plate 163. The cylinder 175^a has a plunger 178 slidably therein which is secured to a plunger rod 179 extending through the head or upper end 180 of the cylinder 175^a. The plunger rod 179 is slidable through guide members 181 and 182 which are secured to the plate 163 in vertically spaced apart relation and the upper end of the rod 179 is provided with a head 183. An abutment 184 is secured to the lower end of the plate 169 and is preferably of convex configuration, and disposed in the path of the head 183 so that when the equalizer 162 is drawn upwardly the head 183 will engage the abutment 184 and thus moves the plunger 178 downwardly in the cylinder 175.

The plunger 178 includes a cup shaped flexible member 185 having upper and lower plates 186 and 187 respectively which engage the upper and lower faces thereof and upper and lower tightening nuts 188 and 189 are threaded onto the rod 179. The rod 179 is provided with a bore 190 opening through the lower end thereof and is also provided with a lateral passage 191 communicating with the upper end portion of the bore 190. A valve seat 192 is formed in the lower end of the bore 190 and a spherical valve 193 is adapted to engage on the seat 192. A plug 194 provided with longitudinal openings 195 is threaded into the lower end of the rod 179 and is adapted to hold the valve 193 in its lowest open position. The upper nut 188 is provided with a horizontal passage 196 which is adapted to communicate with the opening 191, so that air in the upper portion of the cylinder 175 may be vented through the passage 196, passage 191, and downwardly through the bore 190.

A hoisting motor controlling switch 197 is secured to the plate 164 and is provided with an operating arm 198 having a roller 199. A second slide rod 200 is mounted in guide members 201 and 202 fixed to the outer side of the plate

164 and a cushioning spring 203 is disposed about the rod 200 between the guide members 201. A collar 204 is fixed to the rod 200 and bears against the upper end of the spring 203. The lower end of the spring 203 bears against the lower guide member 202. The spring 203 constantly urges the rod 200 upwardly. A spring 205 is disposed about the piston rod 179 between the guide members 181 and 182, and a collar 206 is fixed to the rod 179 and bears against the upper end of the spring 205. The lower end of the spring 205 bears against the lower guide member 181. An L-shaped bracket 207 is fixed to the lower end of the rod 200 and is disposed in the path of the roller 199 carried by the switch operator 198 so that upward movement of the equalizer 162 will effect engagement of the roller 199 with the vertical leg of the bracket 207 to thereby move the lever or arm 198 to a circuit breaking position and thus stop the hoisting motor 170.

A cable 208 is connected to the switch structure 197 and engages through the outer end of a supporting arm 209 which is pivoted as at 210 to the plate 164 adjacent the lower end thereof. The arm 209 is yieldingly held in a substantially horizontal position by means of a spring 211 which is secured at one end to the outer end of the arm 209 and at the other end as at 212 to the upper portion of the equalizing structure. The arm 209 is adapted to support the cable 208 laterally of the load which is carried on the hook 176. A compound switch structure 213 is connected to the lower end of the cable 208 and a strap 214 engages an eye 215 carried by the lower end of the switch structure 213. The strap, 214, is adapted to depend downwardly in a position where it may be grasped by a workman to pull the switch structure 213 downwardly in order that the motor 170 may be operated in the desired manner, and in order that the motor 144 may also be operated in the desired manner.

The motor 144 is adapted to receive its electric current from a pair of trolleys 216 and 217 which are supported by means of transverse bars 218 and insulators 219 and 220 respectively from the upper flange 221 of the monorail structure. A transversely disposed stub shaft or supporting member 221^a is secured to the plate 139 and a second stub shaft 222 is secured to the plate 138 of the rear truck structure. A rock lever 223 is rockably mounted between a pair of ears 224 which are fixed to the shaft 221, and a second rock lever 225 is rockably mounted between ears 226 fixed to the shaft 222. A shoe or wiper 227 is pivotally carried by the upper end of the lever 223 and a shoe 228 is pivotally carried by the upper end of the lever 225. A downwardly projecting rod 229 is fixed to the lever 223 and slidably engaged through a bracket 230 carried by the supporting structure 224. A spring 231 is disposed about the rod 229 and is adapted to yieldingly hold the shoe 227 against the trolley 216. A depending rod 232 is secured at its upper end to the lever 225 and is slidably through a guide 233 extending from the supporting structure 226.

A spring 234 is disposed about the rod 232 below the bracket 233 and is tensioned by means of a nut 235. In this manner the shoe 228, and the same is true of the shoe 221, may be tensioned against the trolley 217. A conductor or wire 236^a is connected to the shoe 228 and is connected as will be hereinafter described to the motor 144. The shoe 227 is also provided with a similar conductor as will be seen from the dia-

grammatic view of the electric circuit which is connected to the motor 144 and also to the motor 170.

The hoist motor 170 also has connected thereto a limit switch 229^a which is supported from the frame structure including the depending members 161 and 164. This switch structure is provided with an operating arm 230^a and a spring 231^a constantly urges the switch arm 230^a to a switch closing position. A horizontally disposed guide member 232^a is secured to the lower end of the frame member 161 and is provided at its outer end with an eye or guide 233^a. A flexible member 234^a is secured at its upper end to the switch arm 230^a and extends downwardly through the eye 233^a. A flexible extension 235^b is connected to the lower end of the chain or flexible member 234^a and is positioned at a point convenient to the operator, and may be used in preference to the switch structure 213.

The motor 144 which moves the hoist or carrier 127 along the rail is connected to switch members 252 and 253 which are secured by means of a supporting arm or bracket 254 to one side of the motor frame or platform 158. The switch structure 252 includes an arm 255 provided with a roller or shoe 256, the purpose for which will be hereinafter described and which is adapted to move the arm 255 to a circuit breaking position. This switch 255 is normally held in a circuit closing position by means well known, in the form of a spring or the like. The switch 253 includes an arm 257 and a shoe or roller 258 which is carried by the arm 257. The switches 252 and 253 are supported laterally of the hoist and are adapted to contact with a switch arm depressor as will be hereinafter described for the purpose of stopping the movement of the hoist or carrier at a predetermined point along the length of the track or monorail.

A pair of normally closed switches 259 and 260 are carried by a supporting bracket or arm 261 secured to the hoist structure opposite from the switches 252 and 253. The switch 259 operates to automatically take up slack in the flexible member 173 and the switch 260 operates to automatically operate the lowering mechanism at a predetermined point in the movement of the hoist. The switch 259 includes an operating arm 262 carrying a roller or shoe 263. The switch 260 has an operating arm 264 carrying a roller or shoe 265. In order to provide a means whereby the hoist may be stopped at predetermined points along the length of the track or monorail, I have provided a pair of switch engaging shoes 266 and 267 which are disposed in the path of the movement of the rollers 256 and 258 respectively. The shoe 266 is carried by an L-shaped slide member 268 which is slidable in a vertical guide 269. The slide member 268 at its upper end is provided with a pair of laterally projecting arms 270 and 271 and the arm 271 is provided with an opening 272 through which one end of a flexible operator 273 is adapted to engage. The operator or cable 273 is trained over a pulley 274 which is supported as at 215 at the upper end of the guide member 269. A horizontally disposed supporting arm 276 is secured to or formed integrally with the guide 269 and engages over the upper flange 221 of the rail. The arm 276 is provided at the free end thereof with a hook or returned portion 277 which engages about an edge of the upper flange 221 and a clamp 278 which is tightened by means of a clamping bolt 279 engages beneath the op-

site edge of the flange 221 so as to hold the supporting arm or bracket 276 in adjusted position at a predetermined point along the length of the track or monorail.

The shoe 267 is secured to the lower end of an L-shaped slide 280 which is slideable in the guide 269 and a flexible member 281 is secured at one end to the upper end of the slide 280. The two flexible members 273 and 281 are connected to a tensioning spring 282 which is secured by a fastening means 283 to a beam or other stationary member 284 at one side and above the rail. In order to provide a means whereby a select one of the two shoes 266 or 267 may be held in inoperative or disengaged position out of the path of the switch operators I have provided an upstanding lug 285 which is fixed to the bracket or arm 276 inwardly from the roller or pulley 274. It will be understood that there may be two of these pulleys 274 and that under normal conditions the flexible member 273 will be engaged over one of the pulleys 274 and the flexible member 271 will be engaged over the other of the pulleys. In practice, however, one of these shoes 266 or 267 will be held in disengaged position while the other of the shoes will be in its lowermost or switch engaging position so that when a selected switch 252 or 253 is in circuit with the motor 144 contact of the roller with a depressed shoe will affect breaking of the circuit to the motor 144 and thus stop the hoist at a predetermined point along the rail. A flexible operating cable 286 is connected to the cable or flexible member 273 and a branch 287 is connected to the cable 286 and to the flexible member 281. This operator 286 is adapted to extend downwardly to a convenient position so that if desired both shoes 266 and 267 may be simultaneously raised or if one of these shoes is in a raised position the depressed shoe may be raised to an inoperative position.

An automatic starter 288 is carried by the hoist frame and is adapted to be connected to the motor 144 in order to provide means for starting or reversing the motor 144. A second automatic starting device and reversing means 289 is also carried by the hoist frame structure and is adapted to be connected to the hoist motor 170. These starting devices 288 and 289 are of conventional and well known construction and it is believed that a further description of these starting devices is not necessary.

In Figures 10 and 11 there is disclosed a slightly modified construction of a load stabilizing member wherein the motor frame member 158a has secured thereto depending plates or arms 161a and 164a. The plates or depending members 161a and 164a are provided with vertical slots similar to the slot 168 and the upper end of the tubular stabilizing member 162a is secured to the depending plates by bolts 290 and 291. The stabilizing member 162a is similar in construction to the stabilizer 162 but is held against undue swinging movement by means of springs 292 and 293 which engage about the bolts 290 and 291 respectively. The bolt 290 has a tensioning nut 294 engaging against a washer 295 which bears against the outer end of the spring 292 and the inner end of the spring 292 bears against a washer 296. A friction plate 297 is secured to the outer face of the depending plate 161a and a second friction plate 298 is secured to the inner face of the plate 161a. A friction plate 299 is secured to the adjacent side of the stabilizer 161a and bears against the plate 298. 70

5 A spring tensioning nut 300 is threaded onto the bolt 291 and a washer 301 is interposed between the nut 300 and the outer end of the spring 293. A washer 302 is interposed between the inner end of the spring 293 and a friction plate 303 secured to the outer side of the depending member 164a. An inner friction plate 304 is secured to the inner side of the depending member 164a and frictionally bears against a plate 305 which 10 is secured to the adjacent side of the stabilizing member 162a. It will be apparent from the foregoing that the tightening of the nuts 294 and 300 will tension the friction plates against each other so as to provide a braking or dampening means to prevent undue swinging movement of the stabilizer 162. A switch 197a comprising a limit switch for the hoist motor is mounted on an L-shaped bracket 306 secured to the upper end of the plate 164a and an operating arm 198a 15 is carried by the switch 197a and connected to the bolt 291 by means of a chain 307 having a spring 308 interposed between the ends thereof. The lower end of the chain 307 engages a head pin 309 which is carried by the outer end of the bolt 291.

25 The switch arm 198a is provided with a stop lug 310 adapted to limit the downward swinging movement of the arm 198a when the bolt 291 is in its lowermost position.

30 A switch member 311 is supported from the front truck plate member 134 in a position for engagement with a bumper 146 of a preceding hoist, and is provided with an operator 312 projecting forwardly of the switch 311 which is 35 adapted to engage a bumper 146 so as to move the switch 311 in a circuit breaking position. This switch 311 is normally held in closed position and is connected to the traveling motor 144.

35 Referring now to the schematic diagram shown in Fig. 14 the shoe 227 is adapted to be connected to conductor 331 which is connected to an armature 332 forming part of the starter 288. A fuse 333 is interposed in the conductor 331. The shoe 228 is connected to a conductor 334 which is connected to a thermo overload structure 335. This 40 overload structure comprises a coil 336 which is connected to the conductor 334 and is connected to a conductor 337. The conductor 337 is connected to the field 338 of the motor 144. The starter 288 includes an electromagnetic coil 339 connected at one side by a wire 340 to the conductor 331. The other side of the coil 339 is connected by a wire 341 to the movable arm 342 of the switch 213. A wire 343 connects one side of the field 338 of the motor 144 to a contact 45 344 associated with the armature or movable starter member 332. A plurality of contacts 345 are connected together by means of wires 346 and provide a step up means for connecting the conductor 331 with the conductor 343. A wire 347 connects the overload switch 335 with one side of an electromagnetic coil 348 and the other side of the electromagnetic coil 348 is connected by a wire 349 to the switch 312. A second electromagnetic coil 350 is connected at one 50 side by a wire 351 to the wire 347 and at the other side by a wire 352 to a contact 353 of the switch 213. A wire 354 connects the wire 349 with a contact 355 of the switch 213.

55 The two coils 348 and 350 comprise part of a reversing switch structure which includes a pair of armatures or switch arms 356 and 357 and a second pair of armatures or switch arms 358 and 359. A stationary contact 360 is associated with the armature or switch arm 356 and is connected by a wire 361 to the connecting wires 346 and

through the conductor 343 to the field 338. A contact 362 is connected by a wire 363 to the opposite end of the field 338. The contact arm 356 is connected by a wire 364 to the contact arm 359 which is connected by a wire 365 to the armature of the motor 144. The contact arm 358 is connected by a wire 366 to the contact arm 357 which is connected by a wire 367 to the opposite side of the motor 144. A contact 368 is disposed in a position for engagement with the contact arm 358 and is connected to the wire 361. A contact 369 is disposed in a position for engagement with the arm 359 and is connected by a wire 370 to the field 338.

The switch 213 includes a contact 371 which is connected by a wire 372 to the switch 253. A wire 373 connects the switch 253 with a manual switch 374. A wire 375 connects one side of the switch 253 with one side of switch 252 and a wire 376 connects the switch 374 with a second manual or shunting switch 377. A wire 378 connects the wires 375 and 376 together between the switches 352 and 353 and the switches 374 and 377. The switch 252 is connected by a wire 379 to the switch 313 and a wire 380 is connected to the switch 377 and the wire 379. The switches 374 and 377 are provided so that either of the switches 353 or 352 respectively may be shunted out so that the circuit breaking shoes 267 and 268 respectively will be ineffective in breaking the electric circuit to the motor 144 and thus permit the hoist to travel to a predetermined point.

The switch 213 includes a second switch structure 213a which as shown in Fig. 14 is connected to the motor 170. The switch 213a includes a wiper 381 which is connected by a wire 382 to the wire 331. A contact 383 carried by the switch 213a is connected by a wire 384 and a wire 385 to a reversing switch structure 289. The wire 385 is connected to a contact 386 which is associated with an armature 387 connected by a wire 388 to the switch 289.

The reversing structure 289 includes a pair of electromagnetic coils 389 and 390. The coil 389 is connected at one side by a wire 391 to a limit switch 392 which has one side thereto connected to the wire 384. The other side of the coil 389 is connected by a wire 393 to a wire 394 connected to one side of the coil 390 and to an overload switch structure 395. The other side of the coil 390 is connected by a wire 396 to one side of the switch 197. The switch 197 is connected on the opposite side to a second limit switch 397 by a wire 398. A wire 399 connects the other side of the limit switch 397 to a contact 400 forming part of the switch 213a. A wire 401 is connected to the wire 399 and to the switch structure 229. A wire 402 is connected through the overload switch 395 to the wire 334 and to the field 403 of the motor 170.

The switch structure 389 includes a pair of switch arms 404 and 405 associated with the coil 389 and a second pair of switch arms 406 and 407 associated with the coil 390. A contact 408 is connected by a wire 409 to the wire 331 and a contact 410 associated with the arm 405 is connected by a wire 411 to the field 403. A contact 412 is connected to the wire 409 and is associated with the arm 406. A contact 413 is associated with the arm 407 and connected by a wire 414 to the field 403. A wire 415 connects the arm 404 with the arm 407 and a wire 416 connects the arm 408 with the arm 405. A wire 417 connects the wire 416 with one side of the 75

armature of the motor 170 and a wire 418 connects the opposite side of the armature 170 with the wire 415.

5 A switch arm 419 is associated with and movable with the arms 406 and 407 and is connected by a wire 420 to one side of the switch 259. A contact 421 is associated with the arm 419 and connected by a wire 422 to the opposite side of the switch 259. A wire 423 connects the wire 420 with the wire 399.

10 The switch structure 213a also includes a contact 424 which is connected by a wire 425 to the wire 388 and also to one side of the switch 260. The opposite side of the switch 260 is connected by a wire 426 to the wire 384. A fuse 427 is interposed in the conductor 334 adjacent the shoe 228.

15 The limit switches 394 and 397 are mounted in a housing 428 and are operatively connected with the drum 172, and are adapted to limit the vertical movement of the hoist in opposite directions. The opposite side of the switch 259 is connected by a wire 429 to the switch structure 229.

20 In order to provide a means whereby the travelling slings or carriers may have the momentum thereof reduced or braked as the slings or carriers approach the weighing stations W, the trolleys 216 and 217 adjacent each weighing station will be provided with reduced electric current sections 216a and 217a respectively, so that when the slings or carriers enter these reduced current sections they will automatically slow down and when they are stopped the load will not swing unduly.

25 In the use and operation of this conveying system, the vessel V is moored to the dock 25 in the usual manner and where the cargo to be removed is disposed in fore and aft holds the vessel is moored with the center of the vessel adjacent the inner ends of the looped rail sections. It will thus be seen that with most vessels at least some portion of each endless rail section will be positioned adjacent the unloading point. At the point where it is desired to stop the empty slings which are carried by the hooks 176 there is positioned a carrier stopping means similar to that disclosed in Figs. 7, 8 and 9. When the carrier has stopped at the desired point, the hoisting mechanism is operated to lower the empty sling. This is done on the vessel side of the rail structure by pulling the cord 235 downwardly so as to close the switch 229 to effect a lowering of the hook 176. When the loaded sling has been transferred to the hook 176, the switch 229 may be operated a second time, there being two positions to this switch as shown in Fig. 23, so as to elevate the loaded sling. The load will continue to rise until the load strikes the lower end of the equalizer sleeve 162, which at this time is in the lowermost position with respect to the elongated opening 168. The tubular member 162 will rise with the load until limit switch 197 breaks the circuit to the motor 170. The travelling motor 144 which at this time is de-energized by opening of a switch 266 by a shoe 268 may be energized by pulling the cord 286 downwardly to raise the shoe 268.

30 The loaded carrier will then proceed on its way around the monorail until it reaches the weighing station W. At this point the carrier will enter the low current zone so that the speed of the carrier will be reduced until it again strikes a shoe 266 or 267 which will again break the circuit to the motor 144. During the move-

ment of the loaded carrier from the loading point to the weighing station, the load has a tendency to slacken. This slack, however, is taken up by providing a sufficiently long shoe 266 which is adapted to engage the roller 263 and effect a closing of the switch 259. Closing of the switch 259 will cause the hoisting motor 170 to tighten up on the load, and in addition place the braking head 183 under the desired tension so as to prevent undue swinging of the 10 load when the carrier stops.

When the weighing operation has been completed the lowered shoe 266 may be raised, thus again closing to the circuit to the carrier motor 144. When the carrier reaches the unloading point, which is adjacent the conveyors 111 and 112, a third carrier stopping means similar to Figs. 7, 8 and 9 will be encountered which will stop the carrier, and at this point the switch 260 will be closed by a suitable shoe 261 so as to close a circuit to the motor 170 and effect an automatic lowering of the load. The load is lowered to the limit permitted by the switch 392 which will automatically break the circuit to the motor 170.

What is claimed is:

1. A travelling hoist comprising a carriage, a support dependingly carried by said carriage, a winding drum carried by said support, operating means for said drum, a flexible member engaging said drum, a sheave engaging said flexible member, an open ended sleeve engaging about said flexible member below said drum, means swingably and slidably supporting said sleeve from said support, a cylinder carried by said sleeve, a plunger slidable in said cylinder, a plunger rod extending upwardly of said cylinder and connected to said plunger, a head carried by the upper end of said rod, guide means for said rod carried by said sleeve, spring means constantly urging said rod upwardly, and a brake shoe fixedly carried by said support above said head and engageable by said head upon upward movement of said rod to thereby hold said sleeve against swinging movement.

2. In an electrically operated travelling hoist, a winding drum carried by said hoist, electrical operating means for said drum, a flexible member wound about said drum, a sheave engaging said flexible member, a draft formed by a plurality of articles held in a sling carried by said sheave for engaging said draft, a tubular member engaging about said flexible member below said drum, means supporting said tubular member for limited vertical movement, said hook adapted to lift said draft against the lower end of said tubular member and raise the latter means carried partly by said tubular member and connected to said operating means for stopping said operating means upon upward movement of said tubular member, and a means in the path of travel of said traveling hoist and operatively connected to said operating means for actuating the latter to take up any slack in said flexible member due to relative movement of the filled bags in the sling during the travel of said traveling hoist.

3. In an electrically operated travelling hoist, a carriage, a motor for said carriage, a hoisting means carried by said carriage, said hoisting means including a flexible load carrying means, a tubular member disposed about said load carrying means, means swingably supporting said tubular member below said carriage, a stationary brake shoe disposed below said car-

riage, and means carried by said tubular member engageable with said brake shoe frictionally resisting swinging movement of said tubular member.

4. In an electrically operated travelling hoist, a carriage, a motor for said carriage, a hoisting means carried by said carriage, said hoisting means including a flexible load carrying means, a tubular member disposed about said load carrying means, means swingably supporting said tubular member below said carriage, a stationary brake shoe disposed below said carriage, and means carried by said tubular member movable longitudinally thereof and engageable with said brake shoe for quickly stopping the swinging movement of said tubular member.

5. In material handling apparatus, in combination, an endless track, an overhead trolley movable along said track, a hoist frame depending from said trolley, a hoisting drum mounted on said hoist frame and having hoisting gear extending downwardly therefrom to sustain a load, reversible driving means for said drum, a vertical stabilizing frame depending from said hoist frame and forming a work passage for said hoisting gear, a pin and slot connection between said hoist frame and said stabilizing frame permitting limited vertical movement of the latter relative to said hoist frame and swinging movement transversely to the direction of movement of said trolley, said hoisting gear adapted to lift and sustain a load against the lower end of said stabilizing frame to prevent movement of said load relative to said stabilizing frame, the load, when raised against said stabilizing frame, lifting the latter relative to said hoist frame, means for selectively starting and stopping said trolley, and means for damping oscillations of said stabilizing frame due to inertia of the latter when starting and stopping said trolley.

6. In material handling apparatus, in combination, a track, an overhead trolley movable along said track, a hoist frame depending from said trolley, a hoisting drum mounted on said hoist frame and having hoisting gear extending downwardly therefrom, driving means for said drum, a vertical stabilizing frame depending from said hoist frame and forming a work passage for said hoisting gear, a pin and slot connection between said hoist frame and said stabilizing frame permitting limited vertical movement of the latter relative to said hoist frame and swinging movement transversely to the direction of travel of said trolley, a draft formed by a plurality of articles held in a sling, said hoisting gear adapted to lift and sustain said draft against the lower end of said stabilizing frame to prevent movement of said draft relative to said stabilizing frame, the draft when raised against said stabilizing frame lifting the latter relative to said hoist frame, means along the path of travel of said trolley and operatively connected to said drum driving means to actuate the latter to take up slack in said hoisting gear created by relative movement between the plurality of articles and sling of the draft during the travel of the trolley along the track, means for selectively starting and stopping said trolley, and means for damping oscillations of said stabilizing frame due to inertia of the latter when starting and stopping said trolley.

7. In material handling apparatus, in combination, an endless track, an overhead trolley

movable along said track, a hoist frame depending from said trolley, a hoisting drum mounted on said hoist frame and having hoisting gear extending downwardly therefrom to sustain a load, reversible driving means for said drum, a vertical stabilizing frame depending from said hoist frame and forming a work passage for said hoisting gear, a pin and slot connection between said hoist frame and said stabilizing frame permitting limited vertical movement of the latter relative to said hoist frame and swinging movement transversely to the direction of movement of said trolley, said hoisting gear adapted to lift and sustain a load against the lower end of said stabilizing frame to prevent movement of said load relative to said stabilizing frame, the load, when raised against said stabilizing frame, lifting the latter relative to said hoist frame, means for selectively starting and stopping said trolley, and pneumatic means for damping oscillations of said stabilizing frame due to inertia of the latter when starting and stopping said trolley.

8. In material handling apparatus, in combination, an endless track, an overhead trolley movable along said track, a hoist frame depending from said trolley, a hoisting drum mounted on said hoist frame and having hoisting gear extending downwardly therefrom to sustain a load, reversible driving means for said drum, a vertical stabilizing frame depending from said hoist frame and forming a work passage for said hoisting gear, a pin and slot connection between said hoist frame and said stabilizing frame permitting limited vertical movement of the latter relative to said hoist frame and swinging movement transversely to the direction of movement of said trolley, said hoisting gear adapted to lift and sustain a load against the lower end of said stabilizing frame to prevent movement of said load relative to said stabilizing frame, the load, when raised against said stabilizing frame, lifting the latter relative to said hoist frame, means for selectively starting and stopping said trolley, and brake means including cooperating friction plate members on said stabilizing frame and said hoist frame for damping oscillations of said stabilizing frame due to inertia of the latter when starting and stopping said trolley.

9. In material handling apparatus, in combination, an endless track, an overhead trolley movable along said track, a hoist frame depending from said trolley, a hoisting drum mounted on said hoist frame and having hoisting gear extending downwardly therefrom to sustain a load, reversible driving means for said drum, a vertical stabilizing frame depending from said hoist frame and forming a work passage for said hoisting gear, a pin and slot connection between said hoist frame and said stabilizing frame permitting

limited vertical movement of the latter relative to said hoist frame and swinging movement transversely to the direction of movement of said trolley, said hoisting gear adapted to lift and sustain a load against the lower end of said stabilizing frame to prevent movement of said load relative to said stabilizing frame, the load, when raised against said stabilizing frame, lifting the latter relative to said hoist frame, means for selectively starting and stopping said trolley, an air cylinder mounted on said stabilizing frame, a plunger reciprocatable in said cylinder, an operating rod for said plunger projecting upwardly from said cylinder, said plunger having an opening for passage of air from one side thereof to the other, spring means normally urging said plunger and operating rod upwardly, an abutment on the under side of said hoist frame in alignment with said operating rod and engageable by the upper end of the latter, and a check valve in the air passage of said plunger permitting flow of air in the cylinder from the upper side of said plunger to the under side thereof and preventing passage of air in the cylinder from the under side of said plunger to the upper side thereof, to dampen any oscillations of said stabilizing frame due to inertia of the latter when starting and stopping said trolley.

10. In material handling apparatus, in combination, an endless track, an overhead trolley movable along said track, a hoist frame depending from said trolley, a hoisting drum mounted on said hoist frame and having hoisting gear extending downwardly therefrom to sustain a load, reversible driving means for said drum, a vertical stabilizing frame depending from said hoist frame and forming a work passage for said hoisting gear, a pin and slot connection between said hoist frame and said stabilizing frame permitting limited vertical movement of the latter relative to said hoist frame and swinging movement transversely to the direction of movement of said trolley, said hoisting gear adapted to lift and sustain a load against the lower end of said stabilizing frame to prevent movement of said load relative to said stabilizing frame, the load, when raised against said stabilizing frame, lifting the latter relative to said hoist frame, coating means carried by said stabilizing frame and said hoist frame and operatively connected to said driving means for stopping said hoisting drum when said stabilizing frame is raised a predetermined distance, means for selectively starting and stopping said trolley, and means for damping oscillations of said stabilizing frame due to inertia of the latter when starting and stopping said trolley.

JACOB H. LIENAU.
JACOB J. NEUMAN.
